US00D749506S

(12) **United States Design Patent**
Morgan

(10) **Patent No.:** **US D749,506 S**
(45) **Date of Patent:** **** Feb. 16, 2016**

(54) **PORTABLE BATTERY CHARGER**

(71) Applicant: **Brand New Days Limited**, Kowloon (HK)

(72) Inventor: **Jeremy Morgan**, Paris (FR)

(73) Assignee: **Brand New Days Limited**, Kowloon (HK)

(**) Term: **14 Years**

(21) Appl. No.: **29/499,166**

(22) Filed: **Aug. 12, 2014**

(51) **LOC (10) Cl.** **13-02**

(52) **U.S. Cl.**

(57) **CLAIM**

What is claimed is the ornamental design for portable battery charger, as shown and described herein.

DESCRIPTION

FIG. 1 is a 3/4 view of a portable battery charger showing the new design;

FIG. 2 is a right side view of the portable battery charger shown in FIG. 1;

FIG. 3 is a left side view of the portable battery charger shown in FIG. 1;

FIG. 4 is a top view of the portable battery charger shown in FIG. 1;

FIG. 5 is a bottom view of the portable battery charger shown in FIG. 1;

FIG. 6 is a front view of the portable battery charger shown in FIG. 1; and,

FIG. 7 is a back view of the portable battery charger shown in FIG. 1.
